Primary Examiner — Karen E Kearney*Assistant Examiner* — Nathaniel D Buckner*(74) Attorney, Agent, or Firm* — Bacon & Thomas, PLLC(57) **CLAIM**

The ornamental design for a network storage device, as shown.

DESCRIPTION

FIG. 1 is a perspective view of a network storage device showing my new design;

FIG. 2 is a front elevation view thereof;

FIG. 3 is a rear elevation view thereof;

FIG. 4 is a top plan view thereof;

FIG. 5 is a bottom elevation view thereof;

FIG. 6 is a left side elevation view thereof; and,

FIG. 7 is a right side elevation view thereof.
